T. J. STEARNS.

CARPET.

No. 16,098.

Patented May 19, 1885.

UNITED STATES PATENT OFFICE.

THOMAS J. STEARNS, OF BOSTON, MASSACHUSETTS, ASSIGNOR TO THE ROXBURY CARPET COMPANY, OF SAME PLACE.

DESIGN FOR A CARPET.

SPECIFICATION forming part of Design No. 16,098, dated May 19, 1885.

Application filed April 20, 1885. Term of patent 3½ years.

To all whom it may concern:

Be it known that I, THOMAS J. STEARNS, of Boston, in the county of Suffolk and State of Massachusetts, have invented a certain new and original Design for a Carpet, of which the following is a specification.

The nature of my design is fully shown and set forth in the accompanying photographic illustration.

10 The design is composed of the diagonal stripes separating the ground of the carpet into rhombic divisions, and the variously-shaped figures and floral ornamentation partly covering said rhombic divisions and stripes.

I claim—

The design for a carpet, substantially as shown and described.

In testimony whereof I have signed my name to this specification, in the presence of two subscribing witnesses, this 14th day of 20 April, 1885.

15 THOMAS J. STEARNS.
